[57] CLAIM

The ornamental design for extensible cradle support for a recreational vehicle drain hose or similar article.

DESCRIPTION

FIG. 1 is a side elevational view of an extensible cradle support for a recreational vehicle drain hose or similar article showing my new design, with a fragmentary side view of a vehicle and a drain hose in broken lines cradled upon the supports;

FIG. 2 is a perspective view of the cradle support in extended length and height when in use;

FIG. 3 is a side elevational view thereof in non-extended horizontal position, and with the extensible legs in uniform length for storage convenience;

FIG. 4 is a top plan view of the design form condition of FIG. 3;

FIG. 5 is a side elevational view opposite to that of FIG. 3;

FIG. 6 is a bottom plan view thereof;

FIGS. 7 and 8 are respectively front and rear elevational views of FIG. 2.

The broken line showing of a fragmentary side elevational view of a recreational vehicle and a drain hose in FIG. 1 is for illustrative purposes only and forms no part of the claimed design.
